GRINDING WHEEL MOUNTING AND
CONTROL

Merton H. Arms and Joseph B. Johnson, Springfield, Vt., assignors to Bryant Chucking Grinder Company, Springfield, Vt., a corporation of Vermont

Application April 23, 1940, Serial No. 331,070

8 Claims. (Cl. 51—50)

This invention relates to the mounting of grinding wheels by which they may be given axial and rotary motions. The axial motions may, if desired, be obtained by fluid pressure mechanism.

One object of the invention is to provide such method in which an accurate and positive control of the grinding wheel is had with simple mechanism.

A further object is to provide for considerable length of wheel path while maintaining the mechanism within a short length except when the long traversing distance is employed.

Further objects and advantages will appear from a more complete description of certain embodiments of the invention shown in the accompanying drawings in which

Figure 1 is a somewhat diagrammatic front elevation illustrating one embodiment of the invention, certain of the parts being shown in section.

Figure 2 is a right hand elevation of the same.

Figure 3 is a detail section on line 3—3 of Figure 1.

Figures 4 and 6 are views similar to a portion of Figure 1, but showing modifications.

Figures 5 and 7 are right end elevations of the structures shown in Figures 4 and 6, respectively.

Figure 8 is a detail section on line 8—8 of Figure 6.

Referring first to the construction shown in Figures 1 to 3, at 1 is indicated the bed of the machine carrying at one end, herein shown the left hand end, a transverse slide 2 carrying a rotary work holder 3. Opposite to this work holder, and as shown, at the right end of the machine, the bed is provided with an upstanding support 5. This support is provided with a bore 6 within opposite ends of which are secured the bearing bushings 7 and 8. Slidably through these bushings is a wheel slide formed by a sleeve 9 having intermediate its length and between the bushings 7 and 8 an enlarged diameter portion 10 forming a piston slidable within the bore 6 and provided with suitable packing rings to make a fluid tight joint therewith.

Journalled within the forward portion of the sleeve 9, and as shown coaxially therewith, is a second sleeve 11 within which is journalled a grinding wheel shaft 12 carrying a grinding wheel 13 at its outer end. As shown the grinding wheel shaft 12 is also coaxial with the sleeves 11 and 9. This shaft at its rear end is coupled by the coupling 14 to a shaft 15 journalled at opposite ends as at 16 and 17 within the sleeve 9. This shaft 15 extends through a cap 18 closing off the rear end of the sleeve 9 and carries outwardly thereof a belt pulley 19. This belt pulley carries a belt 20 which passes around a

driving pulley 21 of a motor 22 which thus rotates the grinding wheel.

The motor 22 is shown as secured to the lower face of a rearward extension of a hood member 23 secured to the sleeve 9 and cap 18 and which arches over and encloses and covers the support 5 and has a skirt 24 which extends down close to the upper face of the bed 1. The bed is provided with a marginal upstanding rib 25 in opposed relation to the lower edge of the skirt 24. Means may be provided for preventing rotation of the sleeve 9. For this purpose, as shown, the forward end of the hood 23 has an opening 28 to receive the sleeve 9 and it extends therebeneath where it supports one end of a guide bar 30 which extends through a perforated lug 31 of the support 5. The rear end of the bar 30 is also carried by the outer end portion of the hood 23 as at 32 above the motor 22.

The axial motion of the wheel is preferably produced by a fluid pressure system, ordinarily hydraulic, and for this purpose pipes 35 and 36 opening into the bore 6 just inwardly of the bushings 7 and 8 and on opposite sides of the piston 10 are provided, these pipes leading to the four-way valve 38 by which they may be selectively brought to register with pressure supply and exhaust pipes 39 and 40, respectively.

In Figures 4 and 5 a slight modification is shown in which instead of supporting the motor on the under side of the hood 23, it is mounted on the end of the hood 23a and its driving shaft 45 may be in alinement with the wheel shaft 12a and may be either a part thereof or be coupled thereto as may be found desirable.

In Figures 6 and 7 provision is made for giving an extended traverse to the grinding wheel beyond what may be obtained by the construction shown in Figures 1 to 5. In this figure the wheel slide support, instead of being a part of the bed of the machine, is a separate slide 50 mounted on ways 51 on the upper face of the bed. This slide 50 has mounted therein the wheel slide sleeve 9 with its piston 10 and carries the sleeve 11 within which the wheel shaft 12 is journaled. This wheel shaft is shown as coupled to the drive shaft 15 in the same way as shown in Figures 1 to 3. This drive shaft is provided with a driving pulley 19. Instead of supporting the driving motor 22b from beneath, it is shown in these figures as supported on the top of the hood member 23 and is belt connected to pulley 19 as by the belt 55. To prevent rotation of the wheel slide, this hood 23 is provided with a guide bar 30b which is slidably guided through a portion of the support 50 and this support 50 is also connected to moving means. As shown it is provided with a depending arm 56 to which is secured the forward end of a piston rod 57 extending into a cylinder 58 where it carries a piston

59 slidable in this cylinder. Fluid under pressure is supplied to either end of this cylinder beyond the piston 59, while being discharged from the other end of the cylinder, through the pipes 60 and 61 leading to the four-way valve 62. Pressure and discharge pipes 63 and 64 communicate with this four-way valve 62 so that the piston 59 may be driven from one to the other end of the cylinder, thus to move the support slide 50 parallel to the movement of the sleeve 9 within the support 59. The slide motion of the sleeve 9 may also be produced, as in the construction of Figure 1, by the four-way control valve 38 which controls the supply and discharge through the pipes 39 and 40 to the pipes 35 and 36 leading to the bore of the support 50 on opposite sides of the piston 10. Thus with this construction there is an additional length of traversing movement for the wheel over that which may be produced by the motion of the sleeve 9 with respect to the support. As shown the two means for producing such motion are independently controlled, each by its own four-way valve 38 or 62.

From the foregoing description of certain embodiments of this invention, it should be evident to those skilled in the art that various changes and modifications might be made without departing from the spirit or scope of this invention as defined by the appended claims.

We claim:

1. In combination, a support having a bore extending therethrough, a member slidable axially within said bore, a rotary tool shaft journaled within said member, means for preventing relative axial motion between said member and shaft, means for rotating said shaft, means for traversing said shaft and member as a unit, and a hood carried by said member and covering said support.

2. In combination, a support having a bore extending therethrough, a member slidable axially within said bore, a bed carrying said support for motion parallel to the motion of said member, a rotary tool shaft journaled within said member, means for preventing relative axial motion between said member and shaft, means for rotating said shaft, means for traversing said shaft and member as a unit, and a hood carried by said member and enclosing a portion of said bed.

3. In combination, a support having a bore extending therethrough, a member slidable axially within said bore, a bed carrying said support for motion parallel to the motion of said member, a rotary tool shaft journaled within said member, means for preventing relative axial motion between said member and shaft, means for rotating said shaft, means for traversing said shaft and member as a unit, and a hood carried by said member and enclosing said support and a portion of said bed.

4. In combination, a support having a bore extending therethrough, a member slidable axially within said bore, a bed carrying said support for motion parallel to the motion of said member, a rotary tool shaft journaled within said member, means for preventing relative axial motion between said member and shaft, means for rotating said shaft, means for traversing said shaft and member as a unit, a hood carried by said member and enclosing said support and a

portion of said bed, and means for moving said support on said bed.

5. In combination, a support having a bore extending therethrough, a pair of bearing bushings spaced axially in said bore, a sleeve slidable axially through said bushings and having an enlarged diameter portion between said bushings forming a piston axially movable within said bore, a rotary grinding wheel shaft journaled in said sleeve, means preventing relative axial motion between said sleeve and shaft, means for rotating said shaft, a fluid pressure mechanism opening into said bore between said bushings on opposite sides of said piston, means for controlling said pressure mechanism to cause traverse of said sleeve and shaft axially, a bar arranged parallel to said sleeve and axially slidable through said support, and means securing said bar to said sleeve.

10 6. In combination, a support having a bore extending therethrough, a pair of bearing bushings spaced axially in said bore, a sleeve slidable axially through said bushings and having an enlarged diameter portion between said bushings forming a piston axially movable within said bore, a rotary grinding wheel shaft journaled coaxially in said sleeve, means preventing relative axial motion between said sleeve and shaft, means for rotating said shaft, a fluid pressure mechanism opening into said bore between said bushings on opposite sides of said piston, means for controlling said pressure mechanism to cause traverse of said sleeve and shaft axially, a bar arranged parallel to said sleeve and axially slidable through said support, and means securing said bar to said sleeve.

15 20 7. In combination, a support having a bore extending therethrough, a pair of bearing bushings spaced axially in said bore, a sleeve slidable axially through said bushings and having an enlarged diameter portion between said bushings forming a piston axially movable within said bore, a rotary grinding wheel shaft journaled coaxially in said sleeve, means preventing relative axial motion between said sleeve and shaft, means for rotating said shaft, a fluid pressure mechanism opening into said bore between said bushings on opposite sides of said piston, means for controlling said pressure mechanism to cause traverse of said sleeve and shaft axially, and a hood carried by said sleeve and enclosing a portion of said support.

30 35 8. In combination, a support having a bore extending therethrough, a pair of bearing bushings spaced axially in said bore, a sleeve slidable axially through said bushings and having an enlarged diameter portion between said bushings forming a piston axially movable within said bore, a rotary grinding wheel shaft journaled coaxially in said sleeve, means preventing relative axial motion between said sleeve and shaft, a fluid pressure mechanism opening into said bore between said bushings on opposite sides of said piston, means for controlling said pressure mechanism to cause traverse of said sleeve and shaft axially, a hood carried by said sleeve and enclosing a portion of said support, and a motor carried by said hood and in driving relation to said shaft.

35 40 9. In combination, a support having a bore extending therethrough, a pair of bearing bushings spaced axially in said bore, a sleeve slidable axially through said bushings and having an enlarged diameter portion between said bushings forming a piston axially movable within said bore, a rotary grinding wheel shaft journaled coaxially in said sleeve, means preventing relative axial motion between said sleeve and shaft, means for rotating said shaft, a fluid pressure mechanism opening into said bore between said bushings on opposite sides of said piston, means for controlling said pressure mechanism to cause traverse of said sleeve and shaft axially, means carrying said support for motion parallel to that of said sleeve, and fluid pressure means for moving said support.
